UNITED STATES PATENT OFFICE.

ALEXANDER FRENCH, OF ELIZABETHTOWN, KENTUCKY.

WIRE-FENCE STAY.

SPECIFICATION forming part of Letters Patent No. 546,280, dated September 10, 1895.

Application filed April 11, 1895. Serial No. 545,350. (No model.)

To all whom it may concern:

Be it known that I, ALEXANDER FRENCH, residing at Elizabethtown, in the county of Hardin and State of Kentucky, have invented 5 certain new and Improved Stay Devices for Wire Fences, of which the following is a specification.

My invention relates to wire stays for holding, stiffening, and supporting the wire strands 10 between the posts and for holding them from sagging, and such invention primarily has for its object to provide a device of this character of a simple and inexpensive nature, which can be quickly and easily applied to permit of a 15 free contraction or expansion of the wire.

Furthermore it has for its object to provide a brace or stay device which will serve to hold the fence level without requiring that the wires be drawn tight, thereby reducing the 20 danger of such wires snapping in cold weather.

My invention also has for its object to provide a sliding-hook stay, which can be applied with the hook end up or down, and a self-closing link member, which will serve to 25 hold the several parts of the stay device in a proper position on the fence-wire.

With other minor objects in view, my invention consists in the peculiar combination and novel arrangement of parts, such as will 30 be first described in detail, and then be specifically pointed out in the appended claims, reference being had to the accompanying drawings, in which—

Figure 1 is a perspective view of a portion 35 of a wire fence with my improved stay devices applied. Fig. 2 is a detail perspective view of the stay, the bottom wire being shown detached. Fig. 3 illustrates the upper hook or bail member before it is bent over the fence- 40 wire. Fig. 4 illustrates the manner in which it is secured thereon. Fig. 5 illustrates the manner in which the slide-hooks are secured on the wires. Fig. 6 illustrates one of the 45 slide-hook members before it is bent over the fence-wire.

Referring to the accompanying drawings, A 50 indicate the posts, which are placed a suitable distance apart; B, the fence-wires or runners; C, the stays, and D a supplemental brace- wire, which is secured to the upper ends of the 55 posts, as shown.

By reference to Fig. 2 the detailed construc-

tion and application of my improved stay will be best understood. The same is formed, preferably, of steel wire in sections, an upper-link 55 member C' and lower slide-hook members C² C², of which as many are used as there are strands or runners. The link member C' is formed of a wire having curved or loop-like ends c', which are bent in reverse directions 60 to hang on the upper or brace-wire D and to support the top strand a, their ends c' joining at a point about midway the strand a and brace-wire D, whereby to form loops c² c², in which the strand D and wire a can have a 65 limited vertical play.

So far as described it will be observed the member c' forms a support for the several wire strands. These strands, it should be stated, are all held from sagging, but to move 70 freely upward, by the peculiar arrangement of the slide-hooks C², which before they are applied to the strands are of a shape shown clearly in Fig. 6 and comprise a main or body portion c³, an eye or hook end c⁴, a laterally-projected loop or eye portion c⁵, and a right-angle projecting portion c⁶. The manner in 75 which the said member is fitted on the strands is best illustrated in Fig. 5, by reference to which it will be seen the end c⁶ is wrapped about the strand a at one side of the upper link or hook member, while its long arm or body is bent down back of the wire a, which brings the loop c⁵ over the link or upper slide-hook member and forms a lock-guide, which 80 prevents such link or hook member from becoming detached from the strand; the lower or loop end c³ is then slipped over the next lower wire, and a second hook-slide C³ is applied thereto in a like manner. 85

From the foregoing description, taken in connection with the drawings, it will be seen the wire strands are positively held from sagging, being supported from the supplemental or brace wire D, while they are held free for a 95 vertical movement upward, to permit the wires being raised or drawn together when it is desired to pass between the same.

Having thus described my invention, what I claim, and desire to secure by Letters Patent, is—

1. In a wire fence, the combination with the horizontal wires, of a link member hung pendent from the uppermost of said wires and a

hook member engaging two of the horizontal wires, its upper end terminating in an eye portion which embraces one of the said horizontal wires and whose terminal is coiled about the wire and separated from the eye by a space which allows lateral play of the link, substantially as described.

2. In combination with the horizontal strands of a wire fence, of a vertical stay device formed of independent sections, each consisting of a body portion terminating at the top in an outwardly projecting eye, and a coil portion wrapped about the wire, and at the lower end in a turned up or hook member, the body portion of one section being held to play in the eye portion of the other all arranged substantially as shown and described.

3. The combination with the wire strands of two or more slide hook members having each a loop portion at the lower end adapted to slip over a lower strand, a body portion extended up to the next upper strand an outwardly bent eye projected over the said upper strand and having the upper end terminating in a coil wrapped about such upper strand, the body portion of one hook member being passed through the eye of the other member all arranged substantially as shown and for the purposes described.

ALEXANDER FRENCH.
